SUBSTITUTED BENZOIC ACIDS, THEIR SALTS AND ESTERS

Quentin E. Thompson, St. Louis, Mo., assignor to Monsanto Chemical Company, St. Louis, Mo., a corporation of Delaware

No Drawing. Application December 7, 1951,
Serial No. 260,569

9 Claims. (Cl. 260—293.4)

1

This invention relates to (alkyl-1-piperidylsulfonyl)-benzoic acids, preferably wherein the alkyl group contains from 1 to 5 carbon atoms, their salts and esters, and to a method for their preparation. The (alkyl - 1-piperidylsulfonyl)-benzoic acids may be represented by the following formula

wherein R represents an alkyl radical, preferably containing from 1 to 5 carbon atoms. The letter "s" in the formula above indicates a saturated ring structure.

The (2 - alkyl - 1 - piperidylsulfonyl) benzoic acids and the (3-alkyl-1-piperidylsulfonyl) benzoic acids, their salts and esters, as described above, contain an asymmetric carbon atom. As a result thereof, these compounds exist in two optically active forms, namely, the dextro-rotary (d) and levo-rotary (l). All such forms and mixtures of these isomers, as well as the (4-alkyl - 1 - piperidylsulfonyl) benzoic acids, their salts and esters, which do not contain an asymmetric carbon atom, are contemplated as coming within the scope of this invention. All of the novel compounds of this invention can be used as intermediates for the preparation of various types of organic compounds. The optically active compounds just referred to may be used as resolving agents or as intermediates for the preparation of other optically active organic compounds. For example, they are useful in the preparation of such resolving agents as the optically active (alkyl-1-piperidylsulfonyl) benzoyl halides, the preparation of which being described in my co-pending application Serial No. 260,568, filed December 7, 1951.

The expression "salts of (alkyl-1-piperidylsulfonyl)benzoic acids" is meant to include the alkali metal and alkaline earth metal salts such as sodium, potassium, lithium, ammonium, magnesium, calcium, the salts of other metals such as copper and iron, and the substituted organic ammonium salts such as the salts of methylamine, trimethylamine, triethylamine, diethylamine, monoethanolamine, triethanolamine, isopropanolamine, pyridine, α -phenylethylamine, morpholine, ephedrine, guanidine, the quaternary ammonium salts such as the tetramethyl ammonium salt, and the like.

The expression "esters of (alkyl-1-piperidylsulfonyl)benzoic acids" is meant to include any

ester of (alkyl-1-piperidylsulfonyl)benzoic acid with any monohydric or polyhydric alcohol which may be either saturated or unsaturated. Typical of such alcohols are primary alkyl alcohols such as methyl alcohol, ethyl alcohol, propyl alcohol, butyl alcohol, amyl alcohol, hexyl alcohol, heptyl alcohol, octyl alcohol, nonyl alcohol, decyl alcohol, undecyl alcohol, dodecyl alcohol, tetradecyl alcohol, cetyl alcohol, and octadecyl alcohol; secondary alkyl alcohols such as isopropyl alcohol, secondary butyl alcohol, secondary amyl alcohol, secondary hexyl alcohol, secondary octyl alcohol and secondary nonyl alcohol; tertiary alkyl alcohols such as tertiary butyl alcohol, tertiary amyl alcohol, tertiary butyl carbinol and tertiary amyl carbinol; the ether alcohols such as ethylene glycol monomethyl ether, ethylene glycol monoethyl ether, and ethylene glycol mono-2-ethylhexyl ether; aromatic alcohols such as benzyl alcohol and methylphenylcarbinol; alicyclic alcohols such as cyclohexanol, cyclobutyl carbinol and cyclopentanol; heterocyclic alcohols such as furfuryl and tetrahydrofurfuryl alcohols; unsaturated aliphatic alcohols such as allyl alcohol, methallyl alcohol, crotyl alcohol and propargyl alcohol; substituted alcohols such as ethylene chlorohydrin, cyanohydrin and 2-bromoethanol; polyhydric alcohols such as ethyleneglycol, diethyleneglycol, glycerol, erythritol, pentaerythritol, and the like.

The novel esters of this invention may be prepared by esterifying (alkyl-1-piperidylsulfonyl)-benzoic acid with an alcohol. In the case of the methyl ester, a particularly convenient method of preparation comprises reacting an (alkyl-1-piperidylsulfonyl)benzoic acid and diazomethane. The novel salts of this invention may be prepared by neutralizing an (alkyl-1-piperidylsulfonyl)benzoic acid with an alkaline derivative of a salt-forming group. The (alkyl-1-piperidylsulfonyl)benzoic acids of this invention may be prepared by reacting a 1-(cyanophenylsulfonyl)-alkylpiperidine having the formula

wherein R represents an alkyl radical, preferably containing from 1 to 5 carbon atoms, and an alkaline derivative of a salt-forming group, thereby forming a salt of an (alkyl-1-piperidylsulfonyl)benzoic acid which may be converted into the free acid by neutralization with a mineral acid. Instead of neutralizing the salt of the

3

(alkyl-1-piperidylsulfonyl)benzoic acid with a mineral acid and recovering the free acid, the salt of the (alkyl-1-piperidylsulfonyl)benzoic acid may be recovered directly.

The following examples are illustrative of the novel compounds of this invention and their method of preparation:

EXAMPLE I

A mixture of 32.0 g. of *dl*-1-(*p*-cyanophenylsulfonyl)-2-methylpiperidine and 400 ml. of a 10% sodium hydroxide solution is refluxed for approximately 2½ hours. The reaction mixture thus obtained is poured while still hot into a mixture of cracked ice and hydrochloric acid, precipitating approximately 34 g. of *dl*-*p*-(2-methyl-1-piperidylsulfonyl)benzoic acid which is recovered by filtration and dried. After recrystallization from chloroform, the *dl*-*p*-(2-methyl-1-piperidylsulfonyl)benzoic acid thus obtained has a melting point of 202°-203° C. and the following analysis:

S
Calculated for C₁₃H₁₇NO₄S ----- 11.32
Found ----- 11.28

EXAMPLE II

The procedure set forth in Example I is repeated utilizing the following ingredients:

32 g. of *d*-1-(*p*-cyanophenylsulfonyl)-2-methylpiperidine
400 ml. of 10% solution of sodium hydroxide

The reaction mixture thus obtained is poured into a mixture of cracked ice and hydrochloric acid, precipitating approximately 34 g. of *d*-*p*-(2-methyl-1-piperidylsulfonyl)benzoic acid which is recovered by filtration and dried. This acid has the following properties:

Melting point, 191°-192° C.
Optical rotation [α]_D²⁵ = +36.96° (c=2, chloroform)

EXAMPLE III

The procedure set forth in Example I is repeated utilizing the following ingredients:

32 g. of *l*-1-(*p*-cyanophenylsulfonyl)-2-methylpiperidine
400 ml. of 10% solution of potassium hydroxide

The reaction mixture thus obtained is poured into a mixture of cracked ice and hydrochloric acid, precipitating *l*-*p*-(2-methyl-1-piperidylsulfonyl)benzoic acid which is recovered therefrom by filtration, and recrystallized from chloroform. This acid has the following properties:

Melting point, 191°-192° C.
Optical rotation [α]_D²⁵ = -36.9° (c=2, chloroform)

EXAMPLE IV

The procedure set forth in Example I is repeated utilizing the following ingredients:

29.2 g. of *d*-1-(*p*-cyanophenylsulfonyl)-2-propylpiperidine
350 ml. of 15% solution of sodium carbonate

The reaction mixture thus obtained is poured into a mixture of cracked ice and hydrochloric acid, precipitating *d*-*p*-(2-propyl-1-piperidylsulfonyl)benzoic acid which is recovered therefrom by filtration and dried.

4

EXAMPLE V

The procedure set forth in Example I is repeated utilizing the following ingredients:

5 32.1 g. of *d*-1-(*m*-cyanophenylsulfonyl)-2-pentylpiperidine
400 ml. of 15% solution of potassium carbonate

The reaction mixture thus obtained is poured into a mixture of cracked ice and hydrochloric acid, precipitating *d*-*m*-(2-pentyl-1-piperidylsulfonyl)benzoic acid which is recovered therefrom by filtration and dried.

EXAMPLE VI

15 The procedure set forth in Example I is repeated utilizing the following ingredients:

26.4 g. of *l*-1-(*p*-cyanophenylsulfonyl)-3-methylpiperidine
350 ml. of 10% solution of sodium hydroxide

The reaction mixture thus obtained is poured into a mixture of cracked ice and hydrochloric acid, precipitating *l*-*p*-(3-methyl-1-piperidylsulfonyl)benzoic acid which is recovered therefrom by filtration and dried.

EXAMPLE VII

The procedure set forth in Example I is repeated utilizing the following ingredients:

30 26.4 g. of 1-(*o*-cyanophenylsulfonyl)-4-methylpiperidine
350 ml. of 10% solution of sodium hydroxide

The reaction mixture thus obtained is poured into a mixture of cracked ice and hydrochloric acid, precipitating *o*-(4-methyl-1-piperidylsulfonyl)benzoic acid which is recovered therefrom by filtration and dried.

EXAMPLE VIII

40 A mixture of 26.4 g. of *dl*-1-(*p*-cyanophenylsulfonyl)-2-methylpiperidine and 350 ml. of a 10% sodium hydroxide solution is refluxed for approximately 2½ hours. On cooling the reaction mixture, the sodium salt of *dl*-*p*-(2-methyl-1-piperidylsulfonyl)benzoic acid is precipitated which is recovered therefrom by filtration and dried.

EXAMPLE IX

50 An excellent yield of ammonium *d*-*p*-(2-methyl-1-piperidylsulfonyl)benzoate is obtained by neutralizing 28.3 g. of *l*-*p*-(2-methyl-1-piperidylsulfonyl)benzoic acid with 25.0 ml. of a 4 molar ammonium hydroxide solution and removing the water by distillation under reduced pressure.

EXAMPLE X

60 An excellent yield of calcium *d*-*p*-(3-ethyl-1-piperidylsulfonyl)benzoate is obtained by neutralizing 28.3 g. of *d*-*p*-(3-ethyl-1-piperidylsulfonyl)benzoic acid with 2.8 g. of calcium oxide in 100 ml. of anhydrous methanol and removing the excess methanol by distillation under reduced pressure.

EXAMPLE XI

70 An excellent yield of the pyridine salt of *o*-(4-propyl-1-piperidylsulfonyl)benzoic acid is obtained by dissolving 31 g. of *o*-(4-propyl-1-piperidylsulfonyl)benzoic acid in 150 ml. of dry pyridine and allowing the solution to cool. In the absence of moisture, the pyridine salt crystallizes out and is removed by filtration, washed with anhydrous ether and dried.

EXAMPLE XII

Methyl *d* - *p* - (2-methyl-1-piperidylsulfonyl) - benzoate is obtained by slowly adding, in increments, a solution comprising 80 ml. of ether and 5 g. of diazomethane to 28.3 g. of *d*-*p*-(2-methyl-1-piperidylsulfonyl)benzoic acid suspended in about 250 ml. of ether. Immediate reaction occurs and the slow addition of the diazomethane solution is continued until the yellow color of diazomethane persists, thereby indicating that all of the acid has been consumed. A large proportion of the excess ether is then distilled from the reaction mixture and a small amount of petroleum ether added, precipitating the desired methyl ester. The methyl ester is recovered by filtration and recrystallized from petroleum ether. Methyl *d* - *p* - (2-methyl-1-piperidylsulfonyl)benzoate has the following properties:

Melting point, 102°-103° C.

Optical rotation $[\alpha]_D^{25} = +34.3^\circ$ (c=2, chloroform)

EXAMPLE XIII

Isopropyl *l* - *p* - (2-methyl-1-piperidylsulfonyl) - benzoate is obtained by reacting 28.3 g. of *l*-*p*-(2-methyl-1-piperidylsulfonyl)benzoic acid and 150 g. of isopropyl alcohol, and removing the water of esterification and the excess isopropyl alcohol by azeotropic distillation.

EXAMPLE XIV

In accordance with the procedure described in Example XIII, an excellent yield of ethylene glycol bis [*d*-*m*-(3-pentyl-1-piperidylsulfonyl) - benzoate] is obtained utilizing the following ingredients:

10 g. of *d*-*m*-(3-pentyl-1-piperidylsulfonyl) - benzoic acid

30 g. of ethylene glycol

While the preceding examples have illustrated specific embodiments of this invention, it will be obvious to those skilled in the art that the reactants and reaction conditions specified in these examples are subject to substantial variation within departing from the scope of this invention. For example, the reaction of the 1-(cyanophenylsulfonyl)-alkylpiperidine and the alkaline derivative of a salt-forming group may be carried out in a wide variety of inert reaction mediums. Water, alkyl alcohols, ethylene glycol, etc., are illustrations of inert reaction mediums which may be used.

The reaction of the 1-(cyanophenylsulfonyl)-alkylpiperidine and the alkaline derivative of a salt-forming group may be carried out over a substantial temperature range, such as at a temperature in the range of from about 60° C. to about 150° C. Preferably, the reaction is carried out by boiling the reaction mixture under reflux conditions. In this reaction the quantities of the reactants utilized is also subject to substantial variation. While equivalent proportions of reactants may be utilized if desired, it is found particularly desirable to use an excess of the alkaline derivative of a salt-forming group. From about 2 to about 10 equivalent proportions of the alkaline derivative of a salt-forming group for each equivalent proportion of the 1-(cyanophenylsulfonyl)-alkylpiperidine is particularly advantageous.

While any alkaline derivative of a salt-forming group can be utilized in this reaction, the carbonates and hydroxides of the desired salt-forming groups are particularly applicable.

The neutralization of the (alkyl-1-piperidylsulfonyl)-benzoic acid with an alkaline derivative of a salt-forming group to form the novel salts of this invention or the esterification of the (alkyl-1-piperidylsulfonyl)benzoic acid with an alcohol to form the novel esters of this invention may be carried out in accordance with any of the standard neutralization or esterification techniques well known to those skilled in the art.

10 The 1-(cyanophenylsulfonyl)-alkylpiperidines utilized in preparing the novel compounds of this invention are described and claimed in my co-pending application Serial No. 256,137, filed November 13, 1951.

15 What is claimed is:

1. As new compositions of matter, compounds of the group consisting of optically active (alkyl-1-piperidylsulfonyl)-benzoic acids, their metal salts, their ammonium and their substituted ammonium salts, said acids having the formula

25

wherein R is a lower alkyl radical and wherein the alkyl-1-piperidylsulfonyl radical is selected from the group consisting of 2-alkyl-1-piperidylsulfonyl and 3-alkyl-1-piperidylsulfonyl radicals.

30 2. As new compositions of matter optically active (2-alkyl-1-piperidylsulfonyl)-benzoic acids having the formula

35

where R is an alkyl radical containing from 1 to 5 carbon atoms.

3. As new compositions of matter optically active (3-alkyl-1-piperidylsulfonyl)benzoic acids having the formula

43

where R is an alkyl radical containing from 1 to 5 carbon atoms.

4. As a new chemical compound, optically active *p*-(2-methyl-1-piperidylsulfonyl)benzoic acid.

5. As a new chemical compound, optically active sodium *p*-(2-methyl-1-piperidylsulfonyl)-benzoate.

6. In a process for the preparation of the compounds of claim 1 the step comprising reacting an optically active 1-(cyanophenylsulfonyl)-alkylpiperidine having the formula

65 wherein R is a lower alkyl radical and wherein the alkyl-1-piperidylsulfonyl radical is selected from the group consisting of 2-alkyl-1-piperidylsulfonyl and 3-alkyl-1-piperidylsulfonyl radicals, with a basic compound selected from the group consisting of salt forming metallo, ammonium and substituted ammonium hydroxides and carbonates.

75

7. In a process for the preparation of the compounds of claim 2 the steps comprising reacting an optically active 1-(cyanophenylsulfonyl)-2-alkylpiperidine having the formula

wherein R is an alkyl radical containing from 1 to 5 carbon atoms with a hydroxide of an alkali metal to form the alkali metal salt of the (2-alkyl-1-piperidylsulfonyl)-benzoic acid, and neutralizing the salt so formed with a mineral acid.

8. In a process for the preparation of the compounds of claim 3 the steps comprising reacting an optically active 1-(cyanophenylsulfonyl)-3-alkylpiperidine having the formula

where R is an alkyl radical containing from 1 to 5 carbon atoms, with a hydroxide of an alkali metal to form the alkali metal salt of the (3-

alkyl-1-piperidylsulfonyl)-benzoic acid and neutralizing the salt so formed with a mineral acid.

9. In a process for the preparation of optically active p-(2-methyl-1-piperidylsulfonyl)-benzoic acid, the steps comprising reacting optically active 1-(p-cyanophenylsulfonyl)-2-methylpiperidine with a hydroxide of an alkali metal to form the alkali metal salt of p-(2-methyl-1-piperidylsulfonyl)-benzoic acid, and neutralizing the salt so obtained with a mineral acid.
